FLATIRON

Edwin E. Arnold, Pittsburgh, Pa., and William J. Russell, Mansfield, Ohio, assignors to Westinghouse Electric & Manufacturing Company, East Pittsburgh, Pa., a corporation of Pennsylvania

Application October 12, 1938, Serial No. 234,628

4 Claims. (Cl. 219—25)

Our invention relates to electrically heated devices, and particularly to flatirons, or the like, having recesses therein for the reception of ceramically insulated heating elements.

5 While the mere inclusion of a helical heating element within an elongated heater recess or slot positioned within the sole plate of a flatiron and suitably insulated therefrom has previously been proposed, the present heating unit assembly is considered to embody valuable and important improvements thereover for the reasons set forth below.

First considering a helically wound resistor or heating element positioned within a heater slot, such heating element cannot produce a sufficient wattage and ironing heat for the present-day requirements of the housewife, inasmuch as the size of the wire used in such element in order to provide the necessary total ohmic resistance, 20 is necessarily relatively small. If it be desired to increase the size of the wire used in such helical heating elements so as to produce an element providing the desired wattage, the diameter of such wire becomes relatively large and of 25 insufficient electrical resistance to permit direct connection across the ordinary domestic supply circuit. Upon making such a coil of increased diameter, in order to overcome this defect, it is evident that a relatively wide trough or slot 30 would be required within the iron, a feature which cannot be employed in an iron of ordinary size because of the necessity of assembling other apparatus therein, such as a thermostat.

In addition, such a wide heater slot necessitates expensive cover plates of corresponding or greater width which have a tendency to warp in use, thus exposing the insulating medium and resulting in its deterioration. Furthermore, in such a wide slot structure substantially one-half 40 of the heat is radiated or conducted upwardly, that is, in a non-useful direction, requiring special heat insulation to prevent overheating the user's hand.

To overcome the disadvantages of a single helical resistance element, it has been proposed to use two helical elements, one above or alongside the other. Such methods, while permitting a certain limited increase in the wattage of such resistance unit as a whole, does not permit full 50 radiation from such resistance element on account of the insulation space inherently present between the two coils and the heat exchange between the coils. In addition, there is, of course, the possibility of short-circuits between 55 the confronting turns of such coils. Moreover,

the use of two side-by-side coils necessarily involves a relatively wide slot, the disadvantages of which have been set forth above.

Consequently it will be appreciated that the prior art was handicapped by serious disadvantages which materially limited the overall delivered heat in flatirons of normal size.

Various metallic covers or cover plates have been devised for mechanically protecting and increasing the thermal efficiency of an iron using 10 heating elements as hereinabove described.

It has been proposed, among other things, to use cover plates initially wider than the groove or heater slot which, in some cases, may have tapered side walls. Such cover plates are in the 15 form of hollow troughs or channels and, upon being pressed downwardly within the slot, their upwardly extending flange portions contact such side walls at acute angles. The friction of such angularly related flanges on the walls thus constitutes substantially the only means for retaining 20 the cover plate within the heater slot. Such construction permits the cover plate to loosen, thus exposing the insulation.

It has also been proposed to use inverted 25 channel-shaped cover plates which have downwardly extending flanges. In such a case, these smooth flanges have even less frictional contact with the side walls, and are forced to rely mainly on their bond with the insulating material to 30 retain their desired location.

A further disadvantage of such proposed cover plates is that in some instances they are necessarily placed in position before the cementitious insulating material has hardened. In other 35 words, a bond between the cementitious insulating material and the cover plate is used to retain the plates in position. This method of retaining the cover plates is very inefficient inasmuch as such bond is readily broken when the iron is 40 jarred or bumped.

In an attempt to overcome this disadvantage, it has been proposed to increase the initial pressure upon the plates. However, due to the insulating material being soft, there is the serious 45 danger of shifting the heating coil or soft insulation, which causes short-circuits between adjacent portions of the element and the walls of the slot.

Consequently it will be appreciated that, in addition to the difficulties and disadvantages of the prior art heating elements, as set forth above, the art has been handicapped by serious disadvantages in the cover plate structure.

In order to overcome all of the difficulties set 55

forth above, and provide a fully satisfactory flatiron of normal size having relatively high delivered heat, we have devised an elliptical or substantially rectangular heating element permitting full direct radiation and conduction of heat through a minimum average thickness of insulation, to the heater slot side walls, which are integral with the base. This construction affords a short, high-capacity metallic path for effecting a maximum delivery of heat. The width of the element is governed by the permissible width of the slot which is usually considerably narrower than its height.

The heating element and insulating material are mechanically protected and retained within the slot by means of an upwardly arched clamping plate which is initially narrower than the slot. The plate upon being subjected to sufficient pressure, flattens or straightens out and forms an intimate metal-to-metal bond or union with the side walls of the slot while further compacting the previously separately hardened insulating material and forcing it to make an intimate bond or union with the slot side walls and the cover plate.

One object of our invention, therefore, is to provide a flatiron having an exceptionally efficient elliptical- or substantially rectangular-sectioned high-wattage heating coil positioned within a relatively narrow elongated heater channel or slot and insulated from the walls thereof by means of a suitable refractory or cementitious material in intimate contact with said walls.

A further object of our invention is to provide a cover plate for heating elements of the type set forth, which will form an intimate metal-to-metal bond or union with the walls of the heater slot.

A still further object of our invention is to provide a flatiron having a slotted sole plate with an elliptically coiled heating element insulatedly disposed therein and an initially arched cover plate therefor, initially narrower than the slot, horizontally engaging the side walls of such slot to form a bond therewith.

Another object of our invention is to provide a flatiron having a slotted sole plate with a ceramically insulated heating element positioned therein and a cover plate therefor which will not be jarred loose from the side walls of the slot, regardless of the usage of the flatiron.

Other objects of our invention will either be pointed out specifically in the course of the following description of a device embodying our invention, or will be apparent from such description.

In the accompanying drawing:

Figure 1 is a side elevational view of the completed iron embodying my invention;

Fig. 2 is a perspective view of the sole plate and heating element associated therewith;

Fig. 3 is a sectional view taken along the line III-III of Fig. 2;

Figs. 4 and 5 are enlarged fragmentary sectional views similar to Fig. 3, showing the cover plate in its various positions;

Fig. 6 is an enlarged fragmentary sectional view similar to Fig. 3, showing the metal-to-metal bond between the cover plate and the slot; and

Fig. 7 is a sectional view illustrating a punch press structure for forming the cover plate.

Referring to the accompanying drawing, we show a flatiron 10 comprising a sole plate 12, a main cover 14 and a handle 16. The sole plate

12 (Fig. 2) has a channel-like slot 18 extending around the sole plate near its edges, so as to define a roughly triangular central recessed area 20 which is adapted to retain a thermostatic switch 21, such as that described and claimed in a copending application of E. K. Clark, Serial No. 237,270, filed October 27, 1938, and assigned to the assignee of our present application. A heating element 22 is surrounded and supported within the slot 18 by insulating material 24, 10 which is retained therein by a clamping cover plate 26, as hereinafter described.

The sole plate 12 is preferably formed from a cast material which, due to the process of casting, produces a rough exterior surface. This roughened surface is easily ground and polished to make a suitable working ironing surface. However, the narrow slot 18, being formed integrally with the sole plate, also has a roughened sand-like wall which aids in retaining the cover plate 26 within the slot 18, as hereinafter described.

The slot 18 is formed primarily by the metallic upwardly extending portions or walls 28 of the sole plate 12. These portions being formed of a heat conducting metal integral with the sole plate, readily and with a maximum efficiency, conduct the heat produced within the slot 18 to the working surface of the sole plate.

The heating element 22 in our structure is formed of a suitable electrical resistance wire into substantially an elliptical or rectangular coiled element, with the longer sides thereof substantially parallel, as shown in Fig. 3. This structure permits the elongated substantially parallel sides of the heating element to be positioned relatively close to the side walls of the slot 18. With the heating element formed in such a manner, it is obvious that substantially all of the heat developed thereby will be readily and efficiently conducted directly to the side walls of the slot 40 and will have to penetrate a minimum average thickness of insulation. In other words, there will not be an inefficient centrally located hot spot.

The heating element 22 is insulated from and supported within the slot 18, with its major axis extending in the direction of the slot depth, by means of a suitable cementitious or ceramic refractory insulating material 24. The insulating material 24 is tightly compressed about the resistance coil 22 and is permanently hardened in a manner as disclosed in a copending application of E. K. Clark, Serial No. 237,167, filed February 18, 1939, and assigned to the assignee of our present application. This method permits the insulating material 24 to be positioned about and within the heating element so as to form a solid homogeneous mass. This heating structure, formed in accordance with the above-identified application, is positioned within the narrow slot 18 as a unit to form a suitable efficient heating element for the flatiron. The cover plate 26 is then positioned over the heating element structure and in close relation thereto for rigidly retaining such structure within the slot 18, as hereinafter described.

The metallic cover plate 26 is preferably formed from a single sheet of metal so as to have an initial cross section narrower than the slot 18 with substantially the same general configuration as the slot. The cover plate is given an initial arch or convex upward curvature (a downward curvature in the punch-press, see Fig. 7) before being initially severed from the stock. Referring 75

to Fig. 7 of the drawing, it will be seen that the die 30 of the punch press, operating within the hold-down plate 32, is formed so as to stretch or shape the plate 26 into an arched position before shearing it from the initial stock plate 31. The cover 26 then retains the initial arch formed therein and remains narrower than the slot 18. The cover plate 26, being narrower and of substantially the same general configuration, is then easily placed within such slot upon the ceramic heating element assembly.

The cover plate 26 is preferably formed as a single solid unitary member. However, if it be desired, the plate may have a series of staggered transverse notches therein to permit more ready expansion and contraction thereof.

In assembling the iron embodying our invention, the sole plate 12 is originally cast, leaving the roughened narrow slot 18 which is substantially narrower than its height. The elliptical heating element 22, being formed substantially the same width as the slot 18 and suitably insulated by a method as described by E. K. Clark in his above-identified copending application, is then positioned within the slot 18 with the parallel sides thereof being positioned close to and parallel with the side walls of the slot 18 so as to be in direct thermal communication with the sole plate 12.

The cover plate 26, initially formed narrower than the slot 18 and having an upwardly arched cross-section, is then positioned within the slot 18 upon the insulated heating element structure as shown in Fig. 4, after hardening of the insulation. A suitable pressure device, not shown, substantially the same general shape as the slot 18, is then positioned upon the cover plate 26 and pressure applied thereto. Inasmuch as the pressure-applying device is substantially the same shape as the slot 18, such pressure applying device will apply a uniform pressure to the cover plate 26 throughout its entire length. In addition, as the cover plate 26 is arched or convexed upwardly, the pressure applying device will then cause the cover plate to become "broken-arched" or to straighten out. During this action, the cover plate will first be retained within the slot by cooperating with the solid insulating material 24, and will then engage the side walls of the slot 18. As the outer edge of the cover plate 26 engages the roughened side walls of the slot 18, the friction therebetween will limit the downward movement of the cover plate.

In addition to the friction between the side walls of the slot 18 and the edges of the cover plate 26, the lower corners of the cover plate edges will bite into the side walls, as the cover plate starts to straighten out. With the continued application of pressure the cover plate 26 will tend to completely straighten out (see Fig. 5), causing the edges of such plate to emboss themselves into the contour of the slot walls as clearly shown in Fig. 6. By embossing we mean that the edge surface of the cover plate will conform to and engage with the irregular surface of the side walls, such as shown in Fig. 6, thereby forming an intimate metal-to-metal bond or union.

In addition to the edges of the cover plate embossing themselves into the contour of the slot walls, such plate will fill the "bite" originally formed in the walls as the plate started to straighten out. In other words, there will be a small substantially triangular portion 35 (see Fig. 6) of the cover which will extend into the slot

side walls. The vertex of this triangular portion will be at the top. Accordingly, with the cover plate extending and embossed into the slot side walls, it will be practically impossible for such cover plate to be removed from the slot, let alone being jarred loose, due to normal usage.

After the cover plate 26 has been broken-arched or straightened, the edges thereof will thus have an intimate metal-to-metal bond therewith. This bond between the cover plate 26 and the slot side walls is of such a character that it hermetically seals such slot to afford full protection for the heating element 22 and insulating material 24.

This "broken-arch" or straightening out method of forming a metal-to-metal bond permits us to use a cover plate of substantial thickness which in itself will be a good heat conductor, ensuring a maximum thermal efficiency for the flatiron, as hereinafter described.

When pressure is applied to cover plate 18 tending to straighten it out, such pressure is imparted to the insulating mass 24. This pressure thus causes the initially hardened insulating material to be further compacted. During this period, in which the insulating material is being compressed and before the cover plate "bites" into the slot side walls, such insulating material is forced to conform to the irregular surface of the slot walls. In other words, the insulating material will be compressed into a homogeneous mass with an intimate bond or union with the slot walls and bottom. This intimate union or bond thus ensures a maximum thermal conductivity between the insulating material and iron sole plate.

The elliptical or substantially rectangular heating element 22 embodied in our invention permits the application of pressure upon the insulating material without any danger of shifting resistors and the consequent danger of short circuits therebetween. In addition, the fact that the elliptical or substantially rectangular heating element 22 is initially set in its illustrated position, surrounded by hardened ceramic insulation, it follows that the element 22 will not shift toward either slot side wall or bottom during the homogenizing of the insulating material.

It, therefore, follows that the elliptical or substantially rectangular shaped heating element 22 permits full direct radiation and conduction of heat to the heater slot side walls so as to effect a maximum delivery of heat to the operating surface of the flatiron, through the cooperation of the metallic slot side walls. In addition, it is obvious that the clamping plate 26, which is initially narrower than the slot 18, upon being subjected to sufficient pressure, expands or straightens out and forms an intimate embossed metal-to-metal hermetically sealing bond or union with the side walls of the slot.

It is further obvious that due to the intimate metal-to-metal bond between the relatively heavy cover plate and the slot side walls, such cover plate will readily conduct the heat which would be radiated upwardly if it were not for the cover plate bond, to the slot side walls. This narrow cover plate structure in combination with the homogeneous insulating mass and substantially rectangular heating element thus ensures a maximum thermally efficient flatiron.

Various modifications may be made in the device embodying our invention without departing from the spirit and scope thereof, and we desire, therefore, that only such limitations shall be

placed thereon as are imposed by the prior art and the appended claims.

We claim as our invention:

5. 1. A flatiron comprising, in combination, a sole plate having formed therein a slot, an electrical heating element disposed within and insulated from the inner walls of such slot, and a cover plate therefor initially narrower than the slot embossed into the side walls thereof.
10. 2. A flatiron comprising, in combination, a sole plate having formed therein a slot, an electrical heating element disposed within the slot, insulating material surrounding and retaining the element therein, and a cover plate therefor, initially narrower than the slot, broken-arched 15 into a metal-to-metal bond with the side walls of the slot.
15. 3. A flatiron comprising, in combination, a sole plate having formed therein a slot, an ellip-

tically coiled electrical heating element disposed within the slot, insulating material surrounding and retaining the element therein, and a cover plate therefor, initially narrower than the slot, engaging the side walls in a plane substantially 5 normal thereto.

4. A flatiron comprising, in combination, a sole plate having formed therein a slot of greater depth than width, an elliptically coiled electrical heating element disposed within the slot with 10 the major axis thereof positioned substantially normal to the base and parallel to the side walls of the slot, insulating material surrounding the element and supporting it within the slot, and a cover plate therefor, initially narrower than 15 the slot, broken-arched into a metal-to-metal bond with the side walls of the slot.

EDWIN E. ARNOLD.
